(57) **CLAIM**

The ornamental design for a vibration motor, as shown and described.

DESCRIPTION

FIG. 1 is a perspective view of the top, front and right side of a vibration motor showing my new design;

FIG. 2 is a perspective view of the bottom, front and left side thereof;

FIG. 3 is a front view thereof;

FIG. 4 is a rear view thereof;

FIG. 5 is a top plan view thereof;

FIG. 6 is a bottom view thereof;

FIG. 7 is a right side view thereof; and,

FIG. 8 is a left side view thereof.

The portions of the article in broken lines are shown for illustrative purposes only and form no part of the claimed design.

1 Claim, 6 Drawing Sheets
